ATTORNEYS'

UNITED STATES PATENT OFFICE.

ALBERT SYDNEY LEEPER, OF KENT, WASHINGTON.

HOLLOW BLOCK AND WALL CONSTRUCTION.

1,290,589.

Specification of Letters Patent.

Patented Jan. 7, 1919.

Application filed July 7, 1916. Serial No. 107,947.

To all whom it may concern:

Be it known that I, ALBERT S. LEEPER, a citizen of the United States, and a resident of Kent, in the county of King and State 5 of Washington, have invented a certain new and useful Improvement in Hollow Block and Wall Constructions, of which the following is a specification:

My invention relates to improvements in 10 hollow block and wall construction in which the hollow block is used, and it consists in the arrangements and combinations herein-after described.

An object of my invention is to provide 15 a hollow block to be used in building construction which is provided with tongues and grooves so arranged that when laid up with mortar the block is locked in position.

A further object of my invention is to 20 provide a block of the type described which can be used to produce walls of different dimensions, the block itself having the approximate dimensions of four ordinary bricks laid one on top of the other with a 25 projection on one side, the projection being the size and shape of an ordinary brick.

A further object of my invention is to 30 provide a wall construction made of the improved hollow block, in which the webs or solid portions of the blocks in different 35 courses are in vertical alinement, and in which the voids are in vertical alinement, and in which the mortar joints are broken between the outside and the inside of the 40 wall by an air space.

A further object of my invention is to 45 provide a wall of the type described having means for permitting the attachment of the wall to studding, without the necessity of cutting, breaking, or otherwise injuring the wall or blocks of which the wall is composed.

Other objects and advantages will appear in the following specification, and the novel features of the invention will be particularly pointed out in the appended claims.

My invention is illustrated in the accompanying drawings forming part of this application, and in which:

Figure 1 is a perspective view of the 50 block;

Fig. 2 is a perspective view of a portion of the wall.

In carrying out my invention I provide a block like that shown in Fig. 1, which consists of side portions 1 and 2 which are 55 parallel and which are joined by parallel

end portions 3 and 4 respectively. Extending between the side portions 1 and 2 is a web 5 which is parallel with the end portions 3 and 4. This web portion it will be 60 noted is toward one end of the block, a void 6 being left between the web 5 and the end 4 while a larger void 7 is left between the web 5 and the end 3. The end 4 is provided with a tongue 4^x running longitudinally of 65 the block, while the end 3 is provided with a groove 3^x. At 8 I have shown a laterally extending tongue or projection which is provided on opposite sides with grooves 8^x and 8^y respectively. It will be noted that this 70 projection or tongue is nearer one end than the other, being substantially twice as far from one end as from the other, or, in other words being situated at a point approximately a third of the distance between the 75 ends 3 and 4 from the end 3.

The wall which forms the subject of the present invention, is one of a number of walls that may be constructed with this 80 block.

It will be seen from Fig. 2 that the blocks are laid in reverse position, and they are not only reversed, but they are inverted; that is to say, the block A at the bottom of the figure has its projection or tongue 8 85 extending to the right, while the block B in the next course above it has its tongue or projection 8 extending to the left. The tongue 8 of the block A is near the bottom end of the block, while the tongue 8 of the 90 block B is near the top end. In order to get this arrangement it is only necessary to reverse the position of the blocks, and to invert them. It will be seen that the tongue 4^x of the block B is contiguous to the groove 95 8^x of the block A. A course of mortar 10 is laid between these portions, and when it hardens locks the block in position. Between the tongue 8 of the block B and the upper end of the block A similar conditions 100 exist. An air space 11 is left between the blocks A and B. The block C which is above the block A is in the same relative position as the block A, and the block D is in the same relative position as the block 105 B, but this leaves the grooves 3^x and 8^y in registration between the blocks B and C, so that when mortar joints 10 are laid, the blocks are locked in position by the key formed when the mortar enters the grooves 110 110 and hardens. The air space 11, however, is formed, and it is in vertical alinement

with the air space 11 in the lower course. This arrangement is followed until the wall is finished. As will be seen from Fig. 2 the blocks A and C are staggered with respect to the blocks B and D, so that the tongues 8 of the blocks A and C are staggered with respect to the blocks B and D so as to break the vertically extending mortar joint.

10 A wall constructed according to my invention has the webs of the blocks or the solid portions thereof in vertical alinement. It has the voids, such as those shown at 6 and 7, in vertical alinement. It is locked vertically by the tongues or extensions 8, and it is locked laterally by the tongues and grooves 4^x, 3^x, 8^x, and 8^y. The mortar joints are discontinuous, that is to say, they are broken by air spaces 11 so that moisture 15 cannot penetrate from the outside of the wall to the inside thereof.

In addition to these advantages, this means of constructing a wall provides opportunity for securing studding, such as 25 that shown at 13, to the wall. To this end it is only necessary to insert the head of a bolt 14 in the space left by the registering grooves 3^x and 8^y and to extend the bolt through the studding which may be drawn 30 up to the wall by means of the nut 15.

I claim:

1. A hollow wall construction comprising horizontal rows of hollow blocks having

laterally extending tongues or projections, the tongues of the blocks in adjacent rows 35 extending in opposite directions to overlie the ends of the body portions of the blocks in adjacent courses, said laterally projecting tongues being provided with grooves on opposite faces, and said body portions being provided with a tongue at one end and a groove at the other arranged to register with certain of the grooves in said tongues of adjacent courses, the contiguous vertical walls of blocks of adjacent courses being 40 spaced apart to provide vertically registering air spaces.

2. A hollow wall construction comprising horizontal rows of hollow blocks having laterally extending tongues or projections, the tongues of the blocks in adjacent rows 45 extending in opposite directions to overlie the ends of the body portions of the blocks in adjacent courses, said laterally projecting tongues being provided with grooves on opposite faces and said body portions being provided with a tongue at one end and a groove at the other arranged to register 50 with certain of the grooves in said tongues of adjacent courses, the contiguous vertical walls of blocks of adjacent courses being spaced apart to provide vertically registering air spaces, the joints between the body portions of the blocks and the tongues of adjacent blocks having a mortar joint.

ALBERT SYDNEY LEEPER.
